UNITED STATES PATENT OFFICE.

EVA LUCRETIA TILLOTSON, OF LONDON, ENGLAND.

SEWING-MACHINE ATTACHMENT FOR PRODUCING TUBES OR COVERING CORES.

1,191,204.

Specification of Letters Patent. Patented July 18, 1916.

Application filed April 21, 1910. Serial No. 556,829.

To all whom it may concern:

Be it known that I, EVA LUCRETIA TILLOTSON, of 76 and 78 High street, London, N. W., England, shop assistant and saleswoman, have invented new and useful Improvements in Sewing-Machine Attachments for Producing Tubes or Covering Cores; and I do hereby declare that the following is a full, clear, and exact description of the same, reference being had to the accompanying drawings, forming a part hereof.

This invention has reference to sewing machine attachments and has for its object to provide an improved device whereby a strip of fabric, leather or other material may be so stitched as to form a tube or roll in such a manner that the raw edges and stitches will be concealed in the interior thereof, said tube or roll being, if desired, filled with cord, twine, whale bone, wool or other material.

In order that my invention may be readily understood and carried into practice, I will now proceed to describe the same fully with reference to the accompanying drawings; in which:—

Figure 1 is a plan view of the complete attachment. Fig. 2 is a collection of four views of the frame A shown in Fig. 1, the central view showing said frame in the same position as in Fig. 1, the right hand view being taken from the right of the first mentioned view, the left hand view being taken from the left of the first mentioned view, and the bottom view being taken from the front of the first mentioned view. Fig. 3 is a collection of three views of the tube B and the arm rigid therewith, one of the views being a plan in the same position as in Fig. 1, the right hand view being taken from the right of the first mentioned view and the lower view being taken from the front of the first mentioned view. Fig. 4 is a group of three views of the guide shield D shown in Fig. 1, one of the views being a plan in the same position as in Fig. 1, the view at the right being taken from the right of the first mentioned view, and the view at the bottom being taken from the front of the first mentioned view. Fig. 5 is a hook or clutch for starting the work through the tube. Fig. 6 is a sectional view on line 6—6 of Fig. 1.

Throughout the separate views the same part is designated by the same reference character.

In Figs. 2, 3 and 4 the arrows indicate the direction in which the view is taken.

Referring more particularly to the drawings, A is a U-shaped frame two sides of which a and d are made thicker and heavier than the third side b, with the consequent formation of a recess as shown at c where the sides of different cross section are joined together. At one end of the frame, that is to say, at the free end of the part a, I provide two recesses o—o' so that the frame can be fixed to a presser bar by the screw already in use for fixing the sewing machine foot or by an accessory screw. It will be seen that the recesses o—o' moreover, are formed in two short walls p and q which are set at right angles to the plane of the side a of the frame and also at right angles to each other.

B is a tube, the use of which will be hereafter described, and at one end of the tube B is an arm e projecting at right angles thereto and fixed securely to the tube B. The arm e is of about the same thickness as the arm b of the frame A and it is intended in assembling the attachments that the arm e should be placed on top of the arm b and fastened thereto so that the part B will project across the open part of the U-frame A and the arm e will fill the recess at the point c. In order that the parts e and b shall be conveniently and firmly fastened together I provide an aperture 1 in the part e and a corresponding aperture near the free end of the part b so that the two parts can be securely screwed together by a small screw such as C which, when in place, will be practically flush with the top face of the part e.

When the parts B and A have been fastened together as just described, the part D is then thrust over the tube B until it reaches the position indicated in Fig. 1. It will be seen that the member D is of sheet metal and comprises two parts 2 and 3 arranged at right angles to each other. It will be understood that the part 2 is somewhat elastic so as to fit closely over the tube B and yet permit the insertion of the cloth between itself and the tube. It will be seen, moreover, that the part 2 is folded over as indicated at 4 so as to partly embrace the tube B on the underside, the part 4 being entirely detached from the part 3 at its lower end. Moreover, the top part of the extension 2 is curved inwardly as indicated

at 5 so as to partly embrace the member B when the whole device is assembled. The front end of the part 3 moreover, is turned downwardly as shown at 6 so that it may fit over the end of the arm e and the corner of the frame A formed by the parts b and d. The part D having been fitted over the part B in the manner just mentioned, D is secured to the frame A by means of a screw 10 E, the frame A having an aperture 7 to receive said screw and the parts e and 3 being provided with apertures 7' and 7", respectively, which register with the aperture 7 when the parts are assembled in Fig. 1. 15 Consequently, the screw E holds the part D to the frame and also passes down the front end of the part e.

The operation of the above described device is as follows:—The attachment being 20 secured to the sewing machine as by the usual accessory screw, after having been assembled as in Fig. 1, one edge of a strip of material which it is desired to form into a roll or tube is passed between the part D and the tube B, the other edge being folded under next to the cloth plate and being guided by the projection 4, which separates the under portion of the cloth from the cloth plate at the right when the parts are viewed 25 as in Fig. 1. As the part D does not extend the entire length of the tube B the two edges of the cloth which have thus been wrapped around B may be alined toward the left end of the tube B. The presser-foot of the sewing machine is then lowered onto the material in the usual way and the machine operated. It will be seen that the two edges 30 of the material will be stitched together and such stitching is continued until the tube of material thus formed projects a short distance beyond the end j of the tube B. Up to this point it will be seen that the edges of the tube of material are on the outside. 35 In order to make a smooth tube the instrument shown in Fig. 5 is then inserted into 40 45

the end K of the tube B and thrust entirely through the tube B and engaged with the material so that it is started into the interior of the tube B, the machine being of course worked at the same time. When the roll 50 of material is of sufficient length it will project from the end K of the tube B so that it can be caught by the hand and the hook or instrument can then be discarded. It will be seen that in this way it can conveniently 55 make a roll or tube of material with the raw edges lying within it and so concealed from view. Moreover, if so desired, the tube so made may be filled with any desired material such as cord, whale bone, wool or the like 60 and this can be done while the outer tube is being made by inserting the filling material into the end j of the tube B.

Having thus described my invention, I 65 claim:—

The combination with a U-shaped plate; of means at the extremity of one leg of the U adapted to attach said plate to a presser bar, the other leg of said U being provided with a screw receiving opening, a tubular 70 member having a flat extension projecting along the last mentioned leg of the U and provided with an opening registering with the first mentioned opening, a guard plate having a lateral extension resting on said 75 flat extension and provided with an opening registering with said openings, said guard plate partly surrounding said tubular member for a portion of its length, and a screw passing through the openings to hold said 80 U-shaped plate, tubular member, and guard plate together and to secure the device to the cloth plate of a machine.

In witness whereof I affix my signature in presence of two witnesses.

EVA LUCRETIA TILLOTSON.
